COUPLING FOR LINE SPACE WHEELS

**Konrad Gebhardt, Nuremberg, Germany, assignor
to Firma Triumph-Werke Nürnberg A. G.,
Nuremberg, Bavaria, U. S. Zone, Germany**

**Application February 24, 1949, Serial No. 78,189
In Germany October 1, 1948**

6 Claims. (Cl. 197—123)

1

This invention relates to certain improvements in the device for coupling the platen or cylinder with the platen ratchet in typewriting, calculating and similar machines. In machines of this kind, the platen gear which is freely rotated with respect to the platen, can be coupled with the platen by a member engaging in an internal toothed thereof.

The conventional couplings for platen ratchets have the drawback that in case of a greater torque to be transmitted to the platen the member engaging in the internal toothed of the platen gear is automatically disengaged, thus causing an unintentional line shifting. It has been attempted to remove this defect by heavy springs. However, the operation of the line space release at the platen is rendered substantially more difficult thereby.

It is the object of the present invention to avoid these drawbacks of the existing devices.

With this object in view, according to the present invention the disengaging pressure acting upon the locking member is taken up by a supporting block or bearing. Thus, automatic disengagement is prevented. The locking member in this case consists of a one-armed lever provided with an oblique slot, in which is moved a clamping angle of sheet metal adapted to be operated by the shaft of the line space release device, and acting as a locking member bearing against the supporting block. One of the legs of the clamping angle is provided with a slot closed on all sides for the passage of the portion of the locking member which defines the radially inner edge of the slot therein. Said leg is under action of a compression spring pressing it automatically into its locking position. A separate clamping angle is provided for each locking member. Thus it is ensured that in case of locking members cooperating with $(n+1)$ or $(n-1)$ teeth of the internal toothed of the platen gear there is always one in fixed engagement while the others bear on the flank or on one of the edges of the internal toothed by action of the spring of the clamping angle. The device according to the invention permits the use of a relatively weak spring for the clamping angle, since it serves merely to cause the clenching without being exposed to the releasing pressure.

The invention will be better understood by reference to the following detailed description in connection with the accompanying drawing showing by way of example and purely schematically one embodiment of the invention and in which:

2

Fig. 1 is a cross sectional view of the device, Fig. 2 is a fragmentary cross section through a locking member in its engaged position, on a larger scale,

5 Fig. 3 is a section similar to Fig. 2, with the locking member disengaged,

Fig. 4 is a view on the front side with the platen shaft and covering disk taken off and the locking members disengaged, on a larger scale,

10 Fig. 5 is a view according to Fig. 4 with the locking members engaged;

Fig. 6 is a view of the clamping angle member. Similar reference numerals denote similar parts in the different views.

15 Referring now to the drawing in greater detail, and first to Fig. 1, it will be seen that the platen 1 at its left face bears a covering cap 2 to which the end capsule 4 and the wedge guide member 5 acting as a supporting block are secured.

20 Secured to the bottom of the end capsule 4 is the holder 6 for the locking members 7 formed as single-armed wedge levers, by means of screws 8. Swingably mounted on the bent off bearing eye 9 of holder 6 at 10, are the wedge levers 7, being secured against lateral deflection in the appertaining slots 11 of the wedge guide member 5 and formed with an oblique slot 16 defined at its radially inner edge by members 17, Figs. 2 and 3.

25 In the end capsule 4 the clamping angles 13 are introduced through bolts 14. In their bent off portion 30 the angles 13 are formed with a recess 31, Fig. 6, for forming the bridge 15, which engages the inclined slot 16 of the wedge lever 7, the clamping angle 13 bearing 30 against the cylindrical surface 18 of the wedge guide 5, Figs. 2 and 4. This arrangement forms a friction ratchet preventing a rearward movement of the wedge lever 7, while not offering any 35 resistance as the clamping angle 13 is pressed back, except for the counterpressure of the springs 12, so that it can easily be released.

The platen gear 19 into whose internal toothed 20 one of the wedge levers 7 is pressed under action of spring 12, is mounted for rotation on the wedge guide member 5 and held by the closure disk 22 fixed by screws 21. Screwed into the wedge guide member 5 is the left hand platen shaft 23 with the platen knob 24 secured thereto.

45 Slidably mounted in the platen shaft 23, against action of spring 27, and secured on the adjusting screw 29, Fig. 1, by the nut 28, is the cylinder release shaft 25 with its cylinder release button 26.

The device acts as follows:

In order to release the platen gear coupling, the button 26, Fig. 1, is pressed inwardly, thereby forcing back the clamping angles 13, by the head of the adjusting screw 29, against action of the springs 12. The bridges 15 of the clamping angles 13 in this case slide in the slots 16 of the wedge levers, swinging them inwardly. The platen gear 19 is now released and the platen 1 can be freely turned, Figs. 3 and 4.

If the cylinder release button 26 is again released after adjustment of the platen 1, the shaft 25 of the cylinder release device is again returned to its normal position, by spring 27, thereby also moving forward the clamping angles 13 by the springs 12, so that the wedge levers 7 are swung outwardly, through bridges 15, into engagement with the internal toothings 20 of the platen gear 19, Figs. 1, 2, and 5.

As will be seen from Fig. 5, the platen gear 19 can be safely locked in any position of the platen 1. The reliability of this locking, as already mentioned, is due to the fact that each of the three wedge levers 7 is held engaged with the internal toothings 20 of the platen gear 19, by a separate clamping angle 13 for each lever 7, the clamping angles 13 owing to their vertical position on the cylindrical part 18 of the wedge guide member 5 forming a reliable frictional locking device having a self-locking effect, by cooperation of the various parts.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In line spacing mechanism for typewriting, calculating and similar machines, in combination with a platen and a line space release shaft, a gear with internal toothings mounted for free rotation on the platen, locking members adapted to engage in said internal toothings for effecting the coupling connection, each locking member having an inclined operating slot, operating means adapted to be moved in said slots under action of the line space release shaft for engaging and disengaging said locking members, and supporting means adapted to take up the pressure acting radially inwardly upon said operating means as a result of the disengaging tendency of the locking members, said locking members, operating means, and supporting means being combined and interrelated in such a way that said inwardly acting radial pressure causes a self-locking friction preventing inadvertent disengagement of the locking members.

2. In line spacing mechanism for typewriting, calculating and similar machines, in combination with a platen and a line space release shaft, a clutch mechanism comprising a gear with internal toothings mounted for free rotation on the platen, a plurality of one-armed levers each having an inclined slot and adapted to engage in said internal toothings for effecting the coupling connection, clamping angle means adapted to be moved in said slots under action of the line space release shaft, and supporting means adapted to take up the pressure acting radially upon said clamping angle means as a result of the disengaging tendency of the levers.

3. In line spacing mechanism for typewriting, calculating and similar machines, in combination with a platen and a line space release shaft, a clutch mechanism comprising a gear with internal toothings mounted for free rotation on the platen, a plurality of one-armed levers each having an inclined slot and adapted to engage in said internal toothings for effecting the coupling connection, clamping angle means for each lever adapted to be moved in the slot of said lever under action of the line space release shaft, one leg of the clamping angle means associated with each lever being provided with a second slot closed on all sides for the passage of a portion of said lever defining the radially inner edge of said inclined slot, and supporting means adapted to take up the pressure acting radially upon said clamping angle means as a result of the disengaging tendency of the levers.

10 4. In line spacing mechanism for typewriting, calculating, calculating and similar machines, in combination with a platen and a line space release shaft, a clutch mechanism comprising a gear with internal toothings mounted for free rotation on the platen, a plurality of one-armed levers each having an inclined slot and adapted to engage in said internal toothings for effecting the coupling connection, clamping angle means having operating legs each adapted to be moved in its associated inclined slot under action of the line space release shaft, each operating leg being provided with a second slot closed on all sides for the passage of a portion of the associated lever forming the radially inner edge of the inclined slot in said lever, compression spring means acting upon the clamping angle means in the direction for engagement of said levers, and a central supporting cylinder adapted to

20 30 35 40 take up the pressure acting radially upon said clamping angle means as a result of the disengaging tendency of the levers.

5. In line spacing mechanism for typewriting, calculating and similar machines, in combination with a platen and a line space release shaft, a clutch mechanism comprising a gear with internal toothings mounted for free rotation on the platen, a plurality of one-armed levers each having an inclined slot and adapted to engage in said internal toothings for effecting the coupling connection, a clamping angle for each lever adapted to be moved in the slot of said lever under action of the line space release shaft, one leg of each clamping angle being provided with a second slot closed on all sides for the passage of a portion of said lever forming the radially inner edge of said inclined slot, and a common central supporting cylinder adapted to take up the pressure acting radially upon each clamping angle as a result of the disengaging tendency of its lever.

6. In line spacing mechanism for typewriting, calculating and similar machines, in combination with a platen and a line space release shaft, a clutch mechanism comprising a gear with internal toothings mounted for free rotation on the platen, a plurality of one-armed levers each having an inclined slot and adapted to engage in said internal toothings for effecting the coupling connection, clamping angle means adapted to be moved in said slots under action of the line space release shaft, and supporting means adapted to take up the pressure acting radially upon said clamping angle means as a result of

the disengaging tendency of the levers, the slope of the inclined slots being such as to cause a self-locking effect against disengaging action.
